UNITED STATES PATENT OFFICE.

WILLIAM HILL AND LAWRENCE GARDELLA, OF OROVILLE, CALIFORNIA.

SMOKING-PIPE.

1,157,161.

Specification of Letters Patent. Patented Oct. 19, 1915.

Application filed January 12, 1915. Serial No. 1,768.

To all whom it may concern:

Be it known that we, WILLIAM HILL and LAWRENCE GARDELLA, citizens of the United States, residing at Oroville, in the county of Butte and State of California, have invented certain new and useful Improvements in Smoking-Pipes, of which the following is a specification.

The present invention relates to smoking pipes, and the invention has for its principal objects to provide a pipe having a metallic bowl and stem support, which structure permits of a thorough sterilizing and cleaning of the pipe without injury to the bowl thereof, and prevents the bowl from absorbing the nicotine and making the pipe strong and disagreeable.

Another object of the invention is to provide a holding device spaced from the bowl which will permit the pipe to be readily grasped in the hand without the danger of the hand being burnt from the heat of the bowl.

With the above mentioned and other objects in view the invention consists in the novel construction and combination of parts hereinafter described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

To more fully comprehend the invention, reference is directed to the accompanying drawing, wherein—

Figure 1 is a longitudinal sectional view of an embodiment of our invention. Fig. 2 is a view in side elevation. Fig. 3 is a view in plan of the pipe bowl. Fig. 4 is a modified form disclosing a support for the protecting means. Fig. 5 is a modified form of fastening the ends of members forming the protecting covering.

Referring more particularly to the several views of the drawings, wherein like characters of reference designate like parts—1 is a pipe, formed of any suitable material, but preferably cast from aluminum, insuring lightness, and the same consists of the usual bowl 2, tubular stem sup-

port 3, and stem 4, which is removably secured in any suitable manner to the stem support. The upper portion of the bowl 2 is formed with an annular flange 5, perforated, as at 6, to permit the heat radiating from the surface of the bowl to pass therethrough, and in said flange are secured at spaced intervals the upper ends of the members or rods 7 of any suitable material. The members 7 are bent to follow the lines of the pipe and are seated at their opposite ends in suitable recesses adjacent to the outer end of the stem support 3, and the same are retained in position preferably by a thimble 8 which encircles the ends thereof.

The members or rods 7 preferably surround the bowl and stem support and provide a protecting covering therefor, which enables the smoker to grasp the pipe without becoming burnt, as in the case with metal pipes as heretofore constructed. The rods or members 7 being spaced from the bowl and stem support admit of air circulating between the same and the bowl or stem support, the circulation of air maintaining the rods or members cool. The rods or members 7 surrounding the stem support and bowl provide a protecting means which admits of a heated pipe being deposited on a table or the like without the heat from the bowl injuring the same.

If desirable an annular supporting spider 9 may be formed on or surround the stem support, as in Fig. 4, and formed with openings through which the members or rods 7 pass, in which case it is not necessary to employ the thimble 8, as the spider 9 forms a support for the members or rods 7 and also maintains the lower ends thereof in uniform spaced relation from each other and from the stem support.

In Fig. 5 we have disclosed a modified form of fastening for the upper ends of the rods or members 7, and in this construction an annular flange 10 is formed surrounding the upper end of the bowl 2, and the upper ends of the rods or members 7 are bent or curved as at 11 and the bent or curved ends thereof are inserted in openings in the outer face of the flange. It is to be understood that the rods or members 7 may be of any desired shape and of any suitable material just so long as the same provide a means

whereby the pipe may be grasped without burning the hands by the heat from the bowl.

Having thus described our invention what we claim is:—

A tobacco pipe comprising a bowl and stem supporting portion, the bowl provided with an annular flange at its upper end and the stem supporting portion formed with an annular groove at its outer end, a protecting covering surrounding the exterior of said bowl and stem supporting portion and comprising a plurality of members

spaced from each other and from the bowl and stem supporting member, and each secured at one end in said flange and at its opposite end in said groove. ¹⁵

In testimony whereof we have signed our names to this specification in the presence of two subscribing witnesses.

WILLIAM HILL.
LAWRENCE GARDELLA.
